UNITED STATES PATENT OFFICE

CLAUDE MARKEL, OF NEW YORK, N. Y.

AUTOMATIC SHUT-OFF DEVICE FOR VALVES

Application filed October 22, 1929. Serial No. 401,438.

This invention is an automatic shutoff device adapted to cooperate with valves such as are customarily employed in controlling flow of gas or other fluid, and the object of 5 the invention, generally speaking, is to provide apparatus which in the event of inadvertent or accidental cessation of the flame fed by said fluid, the valve controlling the feeding thereof will be automatically shut 10 off.

The device of this invention, while adapted for various purposes in this general field of usefulness, is of particular utility in connection with the valves which control the supply 15 of gas to the burners of a gas range, to the pilot light of such a range or to similar heating or ignition adjuncts, water heaters, steam boilers and the like.

Speaking generally, the device of this invention embodies a manually operable member adapted to be so associated with the valve stem that said member may be actuated manually to open the valve and permit the flow of 20 gas or other fluid therethrough. With this member is associated a shutoff element which, when the valve is opened, is moved by said member into a position to be engaged by a thermostatically operable detent and through such movement to energize the spring which 25 tends at all times to move the shutoff element into a position to shut off the valve.

The thermostatic detent is so associated with the shutoff element that when the valve is moved into open position, and the thermostatic element subjected to a predetermined rise in temperature as by lighting the burner of the gas stove with which the device is associated, the detent will be thermostatically moved into engagement with the shutoff element and thus serve to hold such element in retracted position with the valve open so long as the thermostatic detent remains under the influence or heat from the burner. The parts are so constituted, however, that when the heat from the burner falls below a predetermined minimum, as when the burner blows out, the thermostatic detent will be automatically retracted to release the shutoff element and permit the spring to act thereon for the purpose of shutting off the valve in an en-

tirely automatic manner. As stated, the device of this invention is adapted for use in various environments. It embodies numerous novel features of construction and is of unusual simplicity, the working parts being 55 so constituted that they will not be apt to get out of order or fail to function.

Features of the invention other than those specified will be apparent from the following detailed description when read in conjunction 60 with the accompanying drawings and from the appended claim.

In the accompanying drawings, I have shown one practical embodiment of the invention but the construction therein shown 65 is to be understood as illustrative only and not as defining the limits of the invention.

Figure 1 shows the device embodying the present invention in section in the plane of the line 1—1 of Figure 2.

Figure 2 is a section on the line 2—2 of Figure 1 showing center post in elevation and the key and valve in dot and dash lines.

Referring to the drawings, 1 designates the casing of the device. This casing may 75 be made of any appropriate shape or size and may be formed as a casting or in any other desired manner. As shown, however, it is substantially cylindrical and extending co-axially therethrough is a valve post 2. 80 This post is mounted to rotate in perforations in the top and bottom of the casing which form bearings for the post. The bottom or lower end of the post is provided with a polygonal pocket 3 adapted to fit over a 85 correspondingly shaped stem 4 of the valve 5 while the upper end of the post is suitably formed, as by a threaded extension 6, to receive a key or handle 7 by which the post may be operated for the purpose of operating 90 valve stem.

Mounted to rotate freely within the casing, co-axially of the post 2, is a disk 8 which constitutes the shutoff element of the device. This disk is freely rotatable about the post 2 95 and is provided at one point in its periphery with a single notch 9 with which the detent 10 is adapted to cooperate. The detent 10 is in the form of a dog mounted to slide longitudinally of parallel guides 11 formed in 100

the casing so that said detent can move readily into and out of engagement with the notch 9. The detent 10 is, moreover, connected by a rod 12 to any suitable thermostatic mechanism of any conventional form erected in proximity with the burner, pilot light or other source of flame for the continuance of which fluid is fed through a pipe which the valve 5 controls, and the relation of the parts is such that heat derived from the flame will cause the detent 10 to be advanced into the notch 9 whereas an extinguishment of the flame will bring about the lowering of temperature to cause the detent to be retracted from the notch. The detent 10 is shown as controlled by a conventional gas expansion thermostat embodying a diaphragm element 12a and a gas containing bulb 12b.

Extending radially from the post 2 is an operating arm 14 shown in Figure 2 as in the form of a rod threaded through a spacing collar 15 and extending through a perforation cross-axially of the post 2 so as to mount the arm 14 rigid with respect to the post and movable therewith. On the disk 8 is positioned an upstanding pin 16 which projects into the horizontal plane of the arm 14. The spring 17 is anchored at one end to the casing as at 18 and at its other end to the disk 8 as at 19 and serves to normally impel the disk in a counterclockwise direction whereby the pin 16 will force the arm 14 into the dotted line position of Figure 1 wherein it will engage with a stop 20 on the casing. This dotted line position corresponds to the shut-off position of the valve 5 and when the parts are in this position, fluid is precluded from passing through the valve. It will of course be understood that the casing is suitably secured by a bracket 1a or otherwise against movement with respect to the valve. Thus, when it is desired to turn on the valve the handle 7 is grasped and moved in a clockwise direction through substantially ninety degrees to fully open the valve. As the handle is thus turned the operating arm 14 is moved from the dotted line position of Figure 1 into the full line position and during such movement, impels the pin 16 into the full line position of this figure, thus causing the rotation of the shutoff disk into a position wherein the notch 9 will be aligned with the detent 10. Fluid now passes through the valve 5 and may be ignited manually, by a pilot light, or in any other appropriate way, but the handle 7 is manually held until the flame can act upon the thermostatic actuating mechanism to advance the detent 10 into the notch 9. As soon as this has been accomplished, and in practice this requires but a few seconds, the handle may be retracted to a greater or lesser extent as the operator may desire to control the heat of the flame at the burner. Thus, the operator may turn back the handle to partially close the valve and

this operation will manifestly retract the operating arm 14 into, e. g. the dot and dash line position of Figure 1. Nevertheless, the thermostatic detent will hold the shutoff disk against retrograde rotation.

The operator may leave the parts in the position thus described and they will retain this position under normal conditions, until the handle is grasped and the valve closed. If, however, through accident or otherwise, the heat which is maintaining the detent in position fails, as by blowing out of the burner, the detent will automatically be retracted, and as soon as it is withdrawn from the notch, the spring 17 will immediately act to rotate the disk 8 in a counterclockwise direction. In so doing, the pin 16 will engage with the operating arm 14 and force the arm into the dotted line position of Figure 1, thereby shutting off the valve. The valve will remain in shut off condition until it is manually turned on and the fluid re-ignited, as hereinbefore described.

Particular attention is called to the marked simplicity of the device of this invention. It embodies a minimum number of operating parts so constituted that they are not apt to get out of order or fail to operate at any time. The arrangement is economical to manufacture, and can be readily attached to gas ranges, water heaters, and similar constructions with which it is adapted for use.

The foregoing detailed description sets forth the invention in its preferred practical form, but the invention is to be understood as fully commensurate with the appended claim.

Having thus fully described my invention, what I claim as new and desire to secure by Letters Patent is:

A shut off attachment for conventional gas valves comprising a casing, a post rotatably mounted on the casing, said post having a socket at one end and a complementary projection at the other end, a spring tending to impel rotation of the post in one direction, a detent to lock the post in predetermined position with the spring under tension, thermostatic means to control said detent, means for detachably and rigidly supporting the casing in juxtaposition with a conventional valve to be controlled, with the socket at one end of the post interfitting with the end of the valve stem from which the handle has been removed, and a handle secured to the projection at the other end of the post.

In testimony whereof I have signed the foregoing specification.

CLAUDE MARKEL.
